UNITED STATES PATENT OFFICE

EDWARD H. FABRICE, OF CHICAGO, ILLINOIS

DESIGN FOR A BOTTLE

Application filed April 18, 1932. Serial No. 43,529. Term of patent 7 years.

To all whom it may concern:

Be it known that I, EDWARD H. FABRICE, a citizen of the United States and a resident of Chicago, in the county of Cook and State of Illinois, have invented a new, original, and ornamental Design for a Bottle, of which the following is a specification, reference being had to the accompanying drawing, forming a part thereof, wherein:

Fig. 1 is a side elevation and Fig. 2 is a plan view of a bottle embodying my design.

I claim:

The ornamental design for a bottle as shown.

EDWARD H. FABRICE.
